STOVE

Harvey Cory, Chicago, Ill.

Application November 29, 1935, Serial No. 52,028

2 Claims. (Cl. 126—40)

This invention relates to stoves, and particularly such as are adapted for use with coffee makers of various kinds. The present stove is particularly advantageous in restaurants or other public places where large quantities of coffee are prepared and served.

The improvements with which the present invention is concerned relate to the combination of a simple and inexpensive housing with supporting legs that may be fitted in place and furnish adequate support therefor, no matter how heavy the load; with reinforcements which also provide means for securing the supporting legs in place; with further supporting structure within the housing for sustaining the burners that are arranged therewithin; with the utilization of an offset bar adjacent the front wall of the housing, furnishing a depending skirt which serves to carry and conceal a fuel distributing pipe within the housing adjacent its lower edge; and generally with the combination and arrangement of the several elements and units which enter into and form the structure hereinafter described. All such improvements contribute to the strength of the stove structure; to the simplicity of the parts which are required therefor, with a consequent reduction in the expense thereof; to the ease and facility with which these parts may be assembled; and to the general accessibility of the various elements and units in the structure, permitting adjustments, repairs, or replacements as required.

An exemplification of this invention is set forth in the accompanying drawing wherein—

Figure 1 is a view in plan of the stove structure complete, a portion of the top burner plate being broken away to exhibit parts interiorly of the housing;

Fig. 2 is an enlarged transverse section taken on line 2—2 of Fig. 1; and

Fig. 3 is a vertical section taken on line 3—3 of Fig. 1.

The present stove includes in its structure a housing H in the form of an enclosure that may be provided by a band of sheet metal or the like which is extended around with its opposite ends joined at the rear to a connecting plate 5. The corners of the housing are curved as at 6 through a relatively wide arc, instead of being sharp. Across each of the opposite ends of the housing I extend a shelf 7 having a downturned flange 8 whose lower edge may be co-terminus with the corresponding edge of the housing. For a distance of perhaps 90° degrees or more adjacent each corner of the housing, this flange is de-

sirably cut away to avoid difficulties in bending. As by means of spot-weld connections between the flanges and the proximate housing walls each shelf is secured immovably in place.

To support the stove housing in an elevated position, I utilize certain leg blocks L formed desirably from some material which has insulating properties. As shown, each block may be of arcuate shape, so as to fit into a rounded corner of the housing. The cross sectional form of each block (see Fig. 3) is such as to provide a face 10 which is inset adjacent a horizontal shoulder 11. The vertical dimension of this inset face corresponds with that of the shelf flanges 8 whereby the block shoulder and the top surface 15 of the block may furnish supporting engagement to the lower edge of the housing and to the shelf respectively. In addition, each inset block face which is arcuate from end to end in conformity with the corner curvature of the housing is in 20 continuous engagement therewith throughout substantially the entire distance of each flange interruption so as to reinforce the lower edge portion of the housing. To secure each leg block 25 in its supporting position I may utilize a pair of screws 12 which are entered through holes in the shelf to present their shanks in threaded engagement with the body of the leg block.

Along the front wall of the housing and attached to the inner surface thereof at a point 30 near its lower edge, is an offset bar having an upwardly extending flange 15, a horizontal ledge 16, and a depending skirt 17 which lies inwardly of the front housing wall. This bar extends for the major portion of the distance centrally between the two leg blocks at the front of the housing.

The flange 15 may be secured to the housing as by bolt connections 18 or otherwise. Carried by the offset bar, and secured to the ledge 35 thereof as by bolts 20, are one or more horizontally extending clips 21 each bent to form a supporting bracket for a fuel pipe 22. As shown in Fig. 1, this pipe comprises two sections joined by a T-fitting 23 to which is joined another horizontal pipe 24 extending through the rear wall of the housing for connection with a source of fuel supply.

A rear support for the pipe 24 is afforded by an apertured plate 25 through which the pipe is extended, this plate being secured to the rear wall of the housing from which it depends as by a spot weld connection.

Upon the two shelves is mounted a longitudinally extending elevated bracket bar 30. As shown, this bar lies in the rearward portion of the housing, being formed adjacent each end

with a downward extension 31 having an out-turned foot 32 through which may pass a bolt 33 by which the bracket bar is secured in place. The main portion of the bracket bar accordingly 5 lies in a plane which is elevated with respect to the two shelves on which it is supported.

An L-fitting 35 is attached at each of the opposite ends of the pipe 22. Connected with each L-fitting is a nipple 36 which depends from a valve body 37 having a tapered bore wherein is a rotatable plug 38. Extending axially from one end of the plug is a stem 39 which passes through an aperture 40 in the front wall of the housing. An operating handle 41 is fitted to the stem end 10 whereby to rotate the plug through manipulations 15 from the housing exterior.

Connected with the valve body is a nut 45 surrounding the plug stem and serving to confine therearound a coiled spring 46 which bears 20 against a stop plate 47. The plug and stop plate are provided with cooperating elements which limit the turning of the plug to substantially 180 degrees. These and other details of the valve 25 structure which form no part of my invention have been fully disclosed in such publications as the patent to Harper No. 1,964,287 of June 26, 1934.

Through the valve body nipple 36 is a passageway 50 in communication with the fuel pipe 22 through its connection with one of the L-fittings 35. On the plug side opposite the nipple is an extension of the valve body containing a second passageway 51 terminating within an adjustable hood 52 having an orifice 53 adjacent a needle 54. The valve body is also provided with a second nipple 55 having a passageway 56 which communicates with a short passageway 57 extending axially within the plug 38 to join an angular 40 passageway 58 extending transversely therethrough. This transverse passageway is adapted to register fully with either passageway 50 or 51, one at a time, or partly with both simultaneously. Fitted to the nipple 55 is a coupling 68 to which 45 is joined a pipe section 61 leading to a valve body 62 having an adjustable needle valve 63 for controlling the passage of gaseous fuel into a chamber 64 to which air is admitted through a port 65 to support combustion at the discharge end of a 50 pipe 66 forming the secondary unit of a duplex burner.

The primary burner which is concentric with the secondary burner comprises a hollow body having at one end an annular chamber 67 between inner and outer walls 68 and 69 respectively. A series of small burner openings 70 are formed through the top wall of the annulus to assure in operation a circular flame. The burner body extends horizontally from the annulus to 55 provide a lateral passageway 71 having at its end an opening 72 adapted to be fitted over the hood 52. Adjacent its connection with the hood is a side opening 73 adapted to be closed to any extent desired as by means of a valve plate 74 pivoted at 75. Gaseous fuel admitted therethrough the orifice 63 into the passageway 72 is taken into the annular chamber 67 for discharge through the openings 70. Air also enters through the opening 73 to mix with the gaseous fuel, thereby to 60 support combustion of the flames issuing from the burner openings. The body of the primary burner which may be loosely rested at one end upon the hood 52 is supported at its other end upon the bracket bar 39. Desirably a lug 76 depends from the annulus of this burner to lie with-

in an opening 77 which is provided in the bracket bar, whereby the burner plate is held in a fixed operative position.

The burner structure together with the valve mechanism, just described, is duplicated at each end of the stove. One such burner is connected with each of the L-fittings at opposite ends of the pipe 22. Obviously other similar units may be added as required for increase in the stove capacity, but for convenience and simplicity in 10 description and illustration, I have selected a two-burner stove by way of example.

Connected with the T-fitting 23 is an L-fitting 80 to which is connected a coupling 81 joined to a pipe section 82 which extends rearwardly and then upwardly, terminating at a point about midway of the two duplex burners and in line therewith. At the end of this pipe is a small orifice 83 from which may issue a low flame serving as a pilot light. The body of each primary burner 20 is provided with a laterally extending hood 84 wherein may be received one end of a short pipe section 85 which extends laterally toward the pilot flame, terminating just short thereof. This pipe section may be secured in place as by means 25 of a screw 86 which passes through the pipe for engagement with the wall of the hood proximate thereto. The screw may also secure in place a bracket which extends downwardly to provide a foot 87 for resting upon the bracket bar 39, thereby affording a second point of support thereupon for each primary burner body. Through the outer wall 69 of each burner body is a small port or opening 88 through which air or gas may pass. With the burner in operation, air enters through 30 this opening to support combustion, whereas with no combustion a small quantity of gas may escape therethrough into the pipe section 85. The hood 84 is provided with a slot 89 facing upwardly close to one side of the circular row of openings 40 10 in the burner body.

In operation, the control handle 41 may be manipulated to admit gas through either the pipe 61 to the secondary burner 66 or through the passage 51 into the primary burner. Either one 45 of these burners may thereby be operated, according as the valve is manipulated. A pilot light is constantly issued from the orifice 83 between the two pipe sections 85 leading to the hoods which extend laterally from the primary burners. With the valve plug 38 rotated to admit fuel to the primary burner, some of the gas escapes through the port 63 into the adjacent pipe section 85. Upon reaching the pilot light it is ignited and back-fired through the pipe and out through the slot 89 to ignite the gas issuing through the circular row of openings 70 in the primary burner. In the operation of shutting off the primary burner the secondary burner may be opened with the consequence that the latter is ignited from the flames of the former, and vice versa. This follows from the fact that the openings in the valve plug 38 are so arranged that there need not be a complete shutoff of gas to the one burner before opening up communication to the other.

Mounted to rest upon the top edge of the stove housing is a burner plate 90 formed desirably with a depending flange 91 close to its peripheral edge, this flange fitting down and lying within the housing so as to position the plate correctly thereupon. Within the plate are suitable openings 92 for the escape of products of combustion, and directly over each duplex burner is a seat 93 preferably depressed below the plane of the 70 75

burner plate, the seat having a large central opening 94 beyond which are radial ribs 95 on which a cooking utensil may be rested. In this way the heat from the burner therebelow is transmitted directly to the utensil which is thereby supported by the seat in the most effective position.

The stove of this invention is particularly suited for use with gas as fuel, although liquid fuel which is furnished in the proper state or condition may possibly be used as well. It provides in its structure a simple yet strong form of housing for supporting thereabove the burner plate on which one or more cooking utensils are to be rested. In addition it provides interiorly of its structure a mounting for the pipe connections and valve mechanisms, also the several burners that are to be joined thereto, all arranged and combined to operate in the manner hereinbefore set forth. A full flame may issue from each of the primary burners or, if desired, this flame may be shut off and a low flame may be issued from the secondary burners, according to whether or not a cooking temperature is to be maintained or only a serving temperature. A stove having these characteristics is particularly suitable for use in restaurants and other public places in the making and serving of coffee. It is light, easily set up and cared for, and is also ornamental and attractive in appearance.

I claim:

1. A stove having a housing composed of a relatively thin sheet metal band of a width substantially equal to the height of the stove, said band being extended around and joined at its ends to form a continuous band enclosure of generally rectangular configuration, a pair of spaced horizontal shelf-like bottom plates extended across the enclosure at elevations slightly above the

lower edge of the band and shaped to engage and laterally brace the end walls and corner portions formed by said band, corner supporting blocks connected to the underside of the shelf-like plates and embracing the lower band edge portions at the corners, and a rigid burner plate having a depending flange shaped to closely fit within and rest upon the upper edge of said band enclosure, whereby said interfitting parts cooperate to brace and strengthen the relative light supporting and enclosing housing and produce a rigid structure.

2. A stove having a housing composed of a relatively thin sheet metal band of a width substantially equal to the height of the stove, said band being extended around and joined at its ends to form a continuous band enclosure of generally rectangular configuration, a pair of spaced horizontal shelf-like bottom plates extended across the enclosure at elevations slightly above the lower edge of the band and shaped to engage and laterally brace the end walls and corner portions formed by said band, corner supporting blocks connected to the underside of the shelf-like plates and embracing the lower band edge portions at the corners, a rigid burner plate having a depending flange shaped to closely fit within and rest upon the upper edge of said band enclosure, whereby said interfitting parts cooperate to brace and strengthen the relative light supporting and enclosing housing and produce a rigid structure, a burner supporting bracket resting upon and retaining said shelf-like plates in laterally spaced relationship against the inner end walls of said band enclosure, and a burner manifold assembly supported in part by a wall of said band enclosure and said burner supporting bracket in the space between said shelf-like bottom plates.

HARVEY CORY.
